UNITED STATES PATENT OFFICE.

WALDEMAR KOPS, OF NEW YORK, N. Y., ASSIGNOR TO KOPS BROS., OF NEW YORK, N. Y.,
A FIRM.

BRASSIÈRE.

1,294,116.

Specification of Letters Patent. Patented Feb. 11, 1919.

Application filed October 11, 1917. Serial No. 195,883.

To all whom it may concern:

Be it known that I, WALDEMAR KOPS, a citizen of the United States, residing in the borough of Manhattan, city, county, and 5 State of New York, have invented an Improvement in Brassières, of which the following is a specification.

In the manufacture of brassières or corset covers as commonly constructed it has been 10 customary to make the garment so as to open the front with suitable hooks and eyes, clasps and other similar devices by which the adjacent edges of the garment are connected. In some instances however, as shown and de- 15 scribed in Letters Patent No. 1,237,059 granted to me August 14, 1917, brassières of this nature have been provided with suitable devices for properly supporting the busts of the wearer. Also in Letters Patent No. 20 1,253,052 granted to me January 8, 1918 there is shown and described a brassière structure in which the front portion of the body of the brassière is designed to conform to the body of the wearer to properly sup- 25 port the busts, the garment being so constructed as to be adjustable to position at substantially the axillary lines thereof.

The object of the brassière structure as shown in the present case is similar to that 30 Letters Patent No. 1,253,052 aforesaid. In this instance however, the brassière is made of a continuous member preferably comprising front and back portions, the front portion extending between the axillary lines of 35 the body of the wearer with the back portions connected thereto permanently and adapted to be connected so as to properly adjust the garment to position on the wearer in such a manner that it will form an ade- 40 quate support for the busts, and this garment will be hereinafter more particularly described.

In the drawing:

Figure 1 is a rear perspective view illustrating the brassière made in accordance with this invention.

Fig. 2 is an elevation on an enlarged scale showing the outer side of the garment, and

Fig. 3 is an enlarged perspective view 50 illustrating a modified form of the invention.

Referring to the drawing and particularly to Figs. 1 and 2 the brassière preferably comprises a front member 10, which is so 55 shaped as to conform to the bust portion of

the body of the wearer and to extend preferably from one axial line to the other. I also employ back members 11 and 12. The back member 11 is connected to one end of the front member 10 by a suitable reinforcing strip 13 and lines of stitching or otherwise. This back member 11 at its opposite edge is provided with a reinforcing strip 14 secured to which there is a series of hooks indicated at 15. Similarly the back member 12 is connected to the opposite end of the front member 10 by means of a reinforcing strip 16 and suitable lines of stitching. At its opposite edge the back member 12 is provided with a reinforcing strip 17 in which 60 there is a series of spaced eyelets 18. Also connected to and forming part of this back member 12 is a connecting strap 19. In one edge of this connecting strap 19 there is a series of eyelets 20 corresponding in number 65 and position to the eyelets 18 in the reinforcing strip 17. Along its opposite edge the connecting strap 19 is provided with eyes 21 adapted to be engaged by the hooks 15. Laces 22 and 23 are passed through the eyelets 18 and 20 respectively and the corresponding ends of the laces 22 are suitably fixed in the reinforcing strap 17 while the corresponding ends of the laces 23 are fixed in the connecting strap 19. The opposite 70 ends of the laces 22 are brought together and connected to a tape 24 and similarly the opposite ends of the laces 23 are brought together and secured to a tape 25.

The parts of this garment may be pro- 75 vided with shoulder straps 26 and 27 and the back member 11 may be reinforced by a strip 28 and the back member 12 with a similar strip 29.

By reference to Fig. 3 it will be seen that 80 without departing from the nature and spirit of my invention I may dispense with the use of the hooks and eyes by which the ends of the garment are connected in the form of the invention shown in Figs. 1 and 2. In this 85 structure the division of the garment is made centrally at the rear and the laces 22 pass through eyelets 30 and 31 secured respectively in reinforcing strips 32 and 33 se- 90 cured to the adjacent edges of the back mem- bers of the brassière, the laces being secured in a manner similar to that hereinbefore de- 95 scribed.

In the use of the form of this garment as 100 shown in Fig. 2 as will be apparent the hooks 110

are engaged with eyes at the back and the tapes 24 and 25 drawn around the waist exteriorly of the garment to adjust the parts thereof to position so as to properly support 5 the busts of the wearer, and the tapes tied at the front approximately at or slightly above the waist line, whereas in the use of the form of the garment shown in Fig. 3 it is necessary to make the laces sufficiently long to 10 separate the parts of the garment to the required extent to pass the same over the head and shoulders of the wearer before the same is adjusted to position in a manner similar to that hereinbefore described in connection 15 with the form of the invention as shown in Fig. 2.

While in the garments hereinbefore described the front member is a closed or continuous structure made to fit the busts of the 20 wearer, it will be apparent that in either form of the invention, and particularly in that form shown in Fig. 3, the front member of the garment may be divided and provided with suitable clasps by which the front edges 25 of the brassière may be connected to one another.

I claim as my invention:

1. As a new article of manufacture, a brassière comprising a continuous front member 30 constructed to function as a bust supporter, a divided back member connected to the front member, and a series of laces each extending through the end of one back member

and attached to the end of the other back member and adapted to be passed around the waist and secured in position to adjust the brassière to position on the body of the wearer. 35

2. As a new article of manufacture, a brassière comprising a front member formed to 40 function as a bust supporter, a divided back member, and a series of laces in pairs each adapted at corresponding ends to pass through the end of one back member and to be secured to the end of the other back member, the laces at their opposite ends being 45 adapted to be passed around the waist of the wearer and secured in position to adjust and secure the brassière in position on the body of the wearer. 50

3. As a new article of manufacture, a brassière comprising a continuous front member adapted to function as a bust supporter, a divided back member, series of laces in pairs, each of which at corresponding ends is passed 55 through the end of one back member and connected to the end of the other back member, and tapes through which the said pairs of laces are looped and which are adapted to pass around the waist of the wearer and to be secured in position to adjust and secure the brassière in position on the body of the wearer. 60

Signed by me this 8th day of October, 1917.

WALDEMAR KOPS.
